TONE ARM

Roy Dally, Racine, Wis., assignor to Webster Electric Company, Racine, Wis., a corporation of Delaware

Application November 2, 1942, Serial No. 464,201

1 Claim. (Cl. 274—23)

The present invention relates to tone arms, and is particularly concerned with an improved structure for pivotally supporting the tone arm for a limited universal movement.

Another object of the invention is the provision of an improved tone arm construction adapted to be used for sound reproducing apparatus of high fidelity and which is adapted to be used with conventional phonographs to give the best reproduction and minimum record wear, and to eliminate undesirable frequency responses.

Another object of the invention is the provision of an improved light tone arm and reproducer unit structure in which the characteristics of inertia and weight may be conveniently adjusted to any desired value.

Another object of the invention is the provision of an improved form of tone arm pivotal support by means of which the tone arm may be so mounted that it can be lifted up when installed on the phonograph to such position that the bottom of the pickup can be inspected and the needle most conveniently inserted.

Another object of the invention is the provision of an improved tone arm support having a resilient connection between the tone arm and support so that the tone arm can be removed at any time by merely springing apart the pintle supporting springs which are carried by the tone arm support and by means of which any wear may be taken up so that there is no possibility of rattling.

Another object of the invention is the provision of an improved tone arm and reproducer unit which may be manufactured more economically than the devices of the prior art, which may be assembled with less labor, and which requires a lesser number of parts.

Other objects and advantages of the invention will be apparent from the following description and the accompanying drawing, in which similar characters of reference indicate the same parts throughout the several views.

Referring to the single sheet of drawings accompanying this specification,

Fig. 1 is a top plan view of a tone arm and turntable installation embodying the present invention;

Fig. 2 is a full sized bottom plan view of the tone arm removed from its pivotal support;

Fig. 3 is a fragmentary elevational view, with parts of the tone arm and parts of its supporting column in cross section taken on the plane of the line 3—3, looking in the direction of the arrows;

Fig. 4 is a fragmentary sectional view, taken on the horizontal plane of the line 4—4 of Fig. 3, looking in the direction of the arrows.

Referring to Fig. 1, 20 indicates the fixed support for the tone arm 21 and the turntable 22 in the form of the top panel of a phonograph or other housing. The tone arm, which is indicated in its entirety by the numeral 21, includes a pivotal supporting member 23 by means of which the tone arm is mounted for substantially universal movement so that it can be lifted from the record and so that it can progress across the record as its needle follows the groove in the record 24.

15 The tone arm is preferably of a channeled construction, having an upper wall 25 (Fig. 3) and a pair of depending side walls 26 and 27 joined by the partially cylindrical corner portions 28. At its rear or pivotally supported end, it has an end wall 29, closing the end of the channel and joined to the top wall 25 by a partially cylindrical portion 30.

20 The width of the top wall and of the channeled arm preferably increases somewhat from its rear end toward the free or reproducer end, and the channel preferably has an enlargement at its reproducer end, as shown in Fig. 2. At this end the side wall 27 is integrally joined to a side wall portion 31, which extends outward at an angle 30 and is joined to a side wall portion 32, which extends diagonally down toward the other end wall 33 of the channeled arm. The side wall 26 may extend in substantially the same direction throughout its full length to the point where it joins the end wall 33.

25 All of these side wall portions are joined to their respective end wall or other side wall portions by the curved corner walls 34, 35, 36, as indicated in Fig. 2; and the walls of the enlargement, which is indicated in its entirety by the numeral 37, are preferably slightly deeper than the rest of the tone arm so that the enlargement forms a housing 38 which is of greater depth than that portion of the arm which extends backward from it.

30 The enlargement 37 may be provided on its side walls and top wall 39 with a plurality of transversely extending reinforcing ribs 40 (Fig. 1) extending from the bottom of each wall up over the top of the arm and down the other side.

35 The inside of the top wall 25 is preferably formed with a pair of longitudinally extending flanges or ribs 41, 42 (Fig. 2) spaced sufficiently to form a groove which will frictionally retain the conductors 43, 44 leading from the repro-

ducer to the connectors 45, 46. These connectors comprise strips of metal having a head 47 formed at one end and having a body provided with an aperture for receiving a screw bolt 48, which passes through the aperture and is threaded into a lug that is integral with the tone arm.

The other end of each connector, shown at 49, may be of substantially T shape so that its oppositely projecting flanges may be bent about the wire of the insulated conductors 43 or 44 to which they are soldered.

The tone arm may have another integral inwardly projecting cylindrical lug 50 provided with a threaded aperture. Thus the conductors for connecting the pickup in circuit will pass along the tone arm and down through the aperture in the supporting post 51 (Fig. 3) to the electrical circuits which are disposed below the supporting table 20.

The tone arm is preferably provided with a plurality of reinforcing ribs, such as the ribs 52 (Fig. 2), 53, 54 and 55, and at its free end the tone arm is preferably provided with an inwardly projecting cylindrical wall 56, forming a tapered cylindrical socket 57 for receiving a metal body 58 preferably of lead or similar material, having a predetermined amount of inertia.

The lead body 58 is of substantially the same size as the socket 57, and is secured in place by driving it into the socket and spreading it slightly by impact with a tool. It is retained by friction.

The ribs 53, 54 previously mentioned are located at the supported end of the tone arm, and they provide the walls 26 and 27 with sufficient body so that bearing apertures 59, 60 may be of greater length. At its free end the tone arm is preferably provided with a handle 61, and this handle may take the form of a cast metal member, having a supporting portion 62 and a finger piece 63.

The supporting portion comprises a body which is formed on its opposite sides with the parallel grooves 64, 65 of substantially rectangular cross section. These grooves are wide enough to receive the end wall 33 between the walls of the grooves, and the end wall is preferably provided with an upwardly extending slot 66 open at the bottom so that the supporting portion 62 of the handle may be slid upward into the slot 66.

The width of the slot is substantially equal to the width of the body portion 62 between the grooves 64 and 65, and the depth of the slot 66 is equal to the depth of the body portion 62 at this point. The slot 66 is tapered and rounded at the top, and it receives the body portion 62 with a frictional fit of sufficient tightness so that the handle is retained by the tone arm.

The finger portion 63 extends longitudinally outward from the body portion 62, as shown in Fig. 2, and has its lower part provided with a concave surface 67 for engagement with a finger. Its upper side may have a similar curvature.

In addition to serving as a support for the handle, the groove 66 also provides access to the needle-clamping screw 68 (Fig. 2), which is preferably made of the type having a threaded shank and a head with a cruciform socket that requires a special type of tool which the ordinary user may not have, so that he will not tamper with the tone arm.

The tone arm is preferably constructed of cast or molded material. It may be cast of various types of light metals, such as aluminum, or aluminum alloys; but is preferably made of a mold-

ed insulating material, such as a phenolic condensation compound, or some other form of molding powder, such as that called "Bakelite."

All of the parts of the tone arm so far described, except the conductors and connectors, handle and weight, are of one integral piece, so that they may be manufactured economically and require no labor in assembly.

10 Therefore, the relatively light tone arm is provided with the inertia mass previously described, and indicated at 58, which has sufficient inertia so that the tone arm has the proper inertia characteristics. This mass also gives the tone arm sufficient weight at its free end and concentrates the weight at the desired point, so that the needle will track properly in the record groove.

The present tone arm may be equipped with any desirable kind of reproducer or cutter. In the embodiment illustrated, the reproducer 90 is of the crystal type.

Referring to Figs. 3 and 4, the rear end of the tone arm is supported upon the column 51, which comprises a tubular member having a through bore 138, having its upper end formed with a relatively narrow thrust surface. This narrow thrust surface is provided by making the end portion of the bore 138 frusto-conical and by providing a taper 141 at the upper outer surface of the cylindrical column 51.

20 At its lower end this column has a reduced threaded portion 142, and there is an annular shoulder 143, which engages a stamped sheet metal collar 144. The collar 144 has a centrally located bore 145 for passing the reduced threaded portion 142, and it comprises a flange which extends downwardly and radially so that its lower and outer edge 146 is adapted to rest on the phonograph table 20.

30 Provision is made for securing this column 51 to the table 20 by providing the table 20 with a bore 147 for passing the reduced portion 142. A spring washer 148 and nut 149 are threaded on the lower end 142 of the column 51 to clamp the table 20 between collar 144 and nut 149.

40 The cylindrical bore 138 in the column 51 rotatably supports a tubular metal member 150, the upper end of which is expanded into tight frictional engagement in a bore 151 in a metal bracket 152. The bracket 152 has a horizontal flange portion 153 with an aperture having a tight fit with the upper end of the tube 150, and the flange 153 serves as a thrust bearing for the upper end of the tube 150 against the thrust bearing surface 139.

50 A very light spring washer of the wavy type is preferably interposed between flange 153 and thrust bearing surface 139 to prevent any rattling. The lower end of the tube 150 is provided with a half cylindrical groove 154 extending completely around the tube and adapted to receive a round spring wire 155, which is bent to substantially circular form, and which exerts a clamping action that retains it in the groove 154.

60 The spring wire 155 projects beyond the outer surface of the tube 150, and engages the end 156 of the column 51 as a thrust bearing, to keep the tube 150 in the column.

70 The bracket 152, as well as the tube 150, may be constructed of light metal, such as aluminum, or an aluminum alloy, and it is also provided with a vertically extending flange 157.

This flange is at right angles to the flange 153, and it is provided with a through bore 158 at the top for receiving the rubber grommet 159, which is

located in the bore, and which has flanges 160, 161 on both sides of the bracket 152.

The inner cylindrical portion of the grommet also insulates the body of a rivet 162 from the bracket, and this rivet is provided on the left side (Fig. 4) of the bracket 152 with a metal washer 163. The rivet 162 carries a U-shaped spring trunnion supporting member 164. Rivet 162 passes through the grommet 159 and through an aperture in the spring 164 in such manner that the spring 164 is tightly secured to the bracket 152; but there is no metal-to-metal contact between the bracket 152 and the spring 164.

The spring 164 comprises a strip of spring steel bent to substantially U shape and having its yoke 165 provided with the aperture for receiving the rivet 162.

The two legs 166, 167 of this spring extend in the same general direction, but may diverge slightly, as shown in Fig. 4; and at their ends they are provided with apertures for receiving the riveted studs 168, which are similar in shape, but oppositely disposed.

Each stud 168 has an annular shoulder 169, which engages one side of the spring 167 and has a riveted portion on the other side of the spring. The main body of each stud is enlarged, and it is provided with a frusto-conical portion 171 and a reduced cylindrical portion 172.

This reduced cylindrical portion 172 fits in the bearing apertures 59 and 60 of the tone arm, while the frusto-conical portion 171 bears against the end portion of the apertures 59 and 60, and under the resilient compression of the spring arms 166, 167, any wear which occurs in the bearing is taken up and rattling is positively prevented.

The tone arm is thus pivotally supported on the post 51 at an axis, which is disposed very close to the rear wall 29, and the flange 151 is of sufficient length so that as the tone arm pivots upward the rear wall 29 may pivot down into the space which appears between the tone arm in Fig. 12 and the flange 153.

The characteristics of the tone arm and reproducer are greatly improved over the devices of the prior art. There is less needle wear due to the lightness of the tone arm, and the inertia characteristics of the tone arm may be adjusted to any desired value.

By locating the handle 62 and the weight 58 near the free end of the tone arm, its mass is concentrated near the crystal pickup unit and made most effective, and the tone arm may be made much lighter than if the same mass were distributed throughout the full length of the tone arm.

The present tone arm may be manufactured at a very low cost because of the reduction in the

number of its parts, and it may be assembled more quickly than the devices of the prior art in which the reproducer is a separate unit before it is placed in the tone arm.

The present tone arm support is adapted to prevent the transmission of undesirable vibrations to the column and to the support or box of the phonograph, where they would be amplified, and would cause distortion.

While I have illustrated a preferred embodiment of my invention, many modifications may be made without departing from the spirit of the invention, and I do not wish to be limited to the precise details of construction set forth, but desire to avail myself of all changes within the scope of the appended claim.

Having thus described my invention, what I claim as new and desire to secure by Letters Patent of the United States, is:

In a tone arm the combination of a support with a column carried by said support, a tubular shaft rotatably mounted in said column, said tubular shaft carrying a laterally and upwardly projecting metal bracket and said bracket having an aperture in its upwardly extending portion, a tone arm of moldable material having a downwardly open channel and having its rear end curved toward the bottom of said channel, said tone arm having its depending flanges immediately adjacent said rear end provided with a pair of horizontally extending apertures, a resilient U-shaped spring member having an outwardly extending bearing member carried by each of its legs, said bearing members each being provided with a cylindrical portion for reception in said apertures and with a conical portion for taking up wear in said apertures, said U-shaped spring having an aperture in its yoke, a metal rivet having a headed end engaging one inside 40 of said yoke, and said rivet passing through said aperture, said rivet having its body surrounded by a resilient elastic covering provided with flange portions located on each side of said upwardly extending portion of said bracket, and said rivet having its opposite end provided with a thrust member and riveted over, whereby the spring is secured to said bracket without metallic contact between the bracket and spring, said upwardly extending portion of said bracket extending into 45 said tone arm and spacing said tone arm from said tubular shaft, and said horizontally extending apertures being located immediately adjacent a rear wall of said tone arm, whereby the rear wall may be pivoted into a position between said U-shaped spring member and said column when the tone arm is tilted up past the vertical position.

ROY DALLY.
